VACUUM CLEANER WITH AUXILIARY DUST-
RECEIVING BAG

Sherman F. Wells, Minneapolis, Minn.

Application August 21, 1939, Serial No. 291,133

3 Claims. (Cl. 15—9)

My invention relates to vacuum cleaners and provides an improvement thereto, whereby dust mops and the like may be readily cleaned by the action of the vacuum cleaner.

Generally stated, the invention consists of the novel devices, combinations of devices and arrangement of parts hereinafter described and defined in the claims.

Vacuum cleaners, as is well known, very generally include a dust-receiving bag which is pervious to the outward passage of air, but impervious to the passage of dust.

My invention provides an auxiliary or secondary bag into which the dust mop or the like may be inserted for the discharge of lint, dust and the like. This auxiliary or secondary bag is provided with a discharge tube that is connected or connectable to the intake of the fan or blower of the vacuum cleaner. In the preferred arrangement, this auxiliary or secondary bag is incorporated in the dust-receiving bag of the vacuum cleaner. Valve mechanism is provided whereby, when the normal or customary air inlet to the fan is open, the discharge tube from the auxiliary bag will be closed and, conversely, when the main or customary inlet to the fan is closed, the discharge tube from the auxiliary bag will be closed. The invention may be incorporated in connection with any vacuum cleaner of the type including a fan or blower and a dust-receiving bag.

In the accompanying drawings, I have illustrated my invention in what, at the present time, is believed to be a preferred form, incorporated with or applied to a vacuum cleaner of the commercially well-known "Hoover" type.

In the accompanying drawings, which illustrate the invention in the embodiment indicated—

Fig. 1 is a perspective with some parts broken away and some parts sectioned showing the invention applied to a vacuum cleaner of the "Hoover" type;

Fig. 2 is a detail in section on the line 2—2 of Fig. 1; and

Fig. 3 is a perspective with some parts broken away and some parts sectioned showing the lower portion of the vacuum cleaner, the upper portion of the bag structure being removed.

Of the parts of the vacuum cleaner proper, the numeral 5 indicates the box or head; the numeral 6, the dome-like fan casing having the customary main or normal axial air intake port 7; the numeral 8 indicates the rotary fan or blower having the customary shaft 9 driven by the customary electric motor, the casing of which is indicated by the numeral 10; the numeral 11 indicates the air

outlet leading from the fan casing and to which the dust-receiving bag 12 is detachably connected at 13 by the customary or well-known coupling devices indicated at 13. The bag 12 may be of the usual construction, but in this instance will preferably be made larger than usual. The numeral 14 indicates the customary handle-bar, the prongs of which are connected to the box or head 5 in the customary manner. The bag 12 at its upper end is shown as detachably supported from the upper portion of the handle-bar 14 by the customary or any suitable hanger 15.

In accordance with my invention, I provide a secondary or auxiliary flexible bag 16 and this bag, in the preferred arrangement, is placed within the dust-receiving bag 12 with the walls of the latter spaced by webs 17 that are also preferably quite flexible. This auxiliary or dust-receiving bag 16 has a flexible but quite heavy dust-discharge tube 18 that is extended downward and outward through the lower portion of the bag 12 and at its outer end is provided with a tubular coupling 19.

As a means for closing the normal intake 7 to the fan casing, I have shown a cup-like valve head 20 preferably of slightly flexible rubber. This cup valve 20, at its axis, is secured to the flanges of a collar 21 mounted for sliding movements on the fan shaft 9 and through which the fan shaft freely rotates. This cup valve 20 has an outstanding nipple 22 that is connected to a slightly flexible tube 23, the outer end of which is connected to a tubular metallic elbow 24, which latter is extended through and rigidly secured to the air intake shell 5' of the box or head 5. By means of the coupling 19, the outwardly extended end of the discharge tube 18 is normally detachably connected to the extended end of the elbow 24.

In the elbow 24 is a "butterfly" valve 25, the stem of which is provided with an arm 26 and a hand-piece 27. Journaled in and extended through the wall of the shell 5' is a crank shaft 28 provided at its inner end with a crank-pin-equipped head 29 and at its outer end with a crank-head 30, the crank of which latter is connected to the arm 26 by a link 31.

The crank pin of the head 29 works in the slotted intermediate portion of a lever 32, which, at one end, is pivoted to the interior of the shell 5' at 33 and at its other end is forked and engages between spaced collars 34 on the vertically movable valve-actuating sleeve 21.

When the bag 16 is placed within the bag 12 as described, means must be provided for insertion of a mophead 35 or the like and its handle

y' through the walls of both of said bags, so that the mophead can be placed within the inner bag 16. This is preferably accomplished by providing the two bags with a common entrance slot 35 and providing the connecting walls of the two bags with fasteners such as those known to the trade as "Zippers" or as "Talons," indicated at 36.

Operation

- 10 When the vacuum cleaner is to be used in the customary way for the usual purposes, lever 27 will be raised so as to close valve 25 and move cup valve 20 downward into a position to freely open the normal air intake port 7. When the valves are thus set, no air will be drawn from the inner bag 16, but the vacuum cleaner will pick up dust, lint and the like in the usual way and discharge the same into the main bag 12. 15 When lever 27 is pressed downward, valve 25 will open the tube 18 of the inner bag and through lever 32, cup valve 20 will be raised into a position to close the main air intake port 7, thereby causing dust, lint and the like to be drawn from the inner bag downwardly into the fan casing and from thence blown back into the main bag 12. Obviously, the dust mop, when inserted, as shown in the drawings, can be shaken while subject to suction; and if a freer circulation of air is required to discharge the dust, the slot 35 can be more or less opened to admit air. 20 25 30

As already indicated, I have illustrated a preferred embodiment of my invention, but it will be understood that the same is capable of modifications other than those herein indicated, all within the scope of my invention herein disclosed and claimed.

What I claim is:

1. In a self-contained vacuum cleaner, a 40 vacuum fan, a pick-up nozzle, a main dust collecting bag having a mop receptacle directly attached thereto and forming a unitary part thereof, said nozzle and mop receptacle having delivery conduits leading to the intake of said fan, said delivery conduit from said mop receptacle 45 being extended through said main dust collect-

ing bag, said fan having a discharge conduit leading to said main bag, and valve mechanism located in and controlling the opening and closing of said delivery conduits of said nozzle and mop receptacle, said valve mechanism being constructed and arranged, in one position, to simultaneously open the delivery conduit of said nozzle and close the delivery conduit of said mop receptacle, and in another position to simultaneously open the delivery conduit of said mop receptacle and close the delivery conduit of said nozzle. 5 10

2. In a self-contained vacuum cleaner, a vacuum fan, a pick-up nozzle, a main dust collecting bag and an auxiliary bag, said nozzle and auxiliary bag having delivery conduits leading to the intake of said fan, said fan having a discharge conduit leading to said main bag, and valve mechanism located in and controlling opening and closing of the delivery conduits of said nozzle and auxiliary bag, said valve mechanism being constructed and arranged, in one position, to simultaneously open the delivery conduit of said nozzle and close the delivery conduit of said auxiliary bag, and in another position to simultaneously open the delivery conduit of said auxiliary bag and close the delivery conduit of said nozzle, said auxiliary bag being located within said main bag and being provided with an opening through which a dust mop or the like may be inserted into said auxiliary bag. 20 25 30

3. In a self-contained vacuum cleaner, a vacuum fan, a pick-up nozzle, a main dust collecting bag and an auxiliary bag, said nozzle and auxiliary bag having delivery conduits leading to the intake of said fan, said fan having a discharge conduit leading to said main bag, and valve mechanism located in and controlling opening and closing of the delivery conduits of said nozzle and auxiliary bag, said auxiliary bag being located within said main bag and being provided with an opening through which a dust mop or the like may be inserted into said auxiliary bag. 35 40 45
